UNITED STATES PATENT OFFICE

JOHN W. CERNY, OF DENVER, COLORADO

RAILWAY HIGHWAY CROSSING

Application filed December 30, 1930. Serial No. 505,497.

This invention relates to a railway highway crossing and more particularly to an improved construction thereof.

Many types of such crossings have been suggested and employed, such crossings being of the metal, wooden or other types. All of such structures known to me do not possess the rugged endurance required. This is due for the most part to the peculiar office held by the crossing. The tremendous weight and pounding to which the traffic rails and the adjacent crossing members are subjected cause a situation that has been heretofore overlooked. The most conventional practice is to provide, on the inner sides of the traffic rails, what is known as a flangeway rail, the latter being nothing more than a traffic rail disposed at 90 degrees to the traffic rail, having the ball portion or the upper portion of the flangeway rail abutting the web of the traffic rail. This structure is generally accepted as the answer to the provision of a flangeway. However, the heretofore referred to pounding of the train wheels develops a pumping action within the flangeway which forces into the intermediate crossing structure dirt and dust of inferior grade together with water, and during the winter seasons the freezing of this mixture of water and dust and the like, pries the crossing members apart distorting the crossing surface.

It is one object of this invention to provide a railway highway crossing so constructed as to overcome the above difficulties.

Another object is to provide a novel railway highway crossing in which inverted channel iron members placed in spaced relation, are utilized to form a desirable and durable crossing surface.

Another object is to provide a railway highway crossing in which the several members are so positioned as to form a seal so as to exclude from those parts of the structure water and foreign substances which would cause damage to the crossing during freezing weather.

A further object is to provide novel means for supporting the flangeway rail so that proper drainage is afforded and the misplacement of the flangeway rail obviated.

The above and other objects will be made apparent throughout the further description of the invention taken in connection with the accompanying drawings, wherein like reference characters refer to like parts. It is to be expressly understood that the drawings are not a definition of the invention, the latter being expressed in the scope of the appended claims.

In the drawings:

Figure 1 is a perspective view, partly in section, of a railway highway crossing embodying the invention.

Figure 2 is a sectional view taken along the line 2—2 of Fig. 1.

Figure 3 is a partial plan view embodying the invention but illustrating the structure when the crossing occurs at a rail joint.

Figure 4 is an enlarged detail sectional view embodying the invention, and

Figure 5 is an enlarged detail view of one of the flangeway rail supporting members.

Referring to the drawings, the preferred embodiment illustrated includes a supporting surface 10, which may be earth, concrete or other suitable material, having positioned thereon the usual cross-ties 11, for supporting track rails 12, the latter being mounted immediately on tie plates 12a, secured to the cross-ties by the same spikes 13, which secure the rail to the ties.

The crossing, and especially that portion located intermediate of the rails 12, comprises a plurality of filler members 14, disposed in parallel relation one to the other and spaced apart by spacing sticks 15, the latter being of such height as to extend upwardly for the greater portion of the depth of the filler members 14, the purpose of which will be later described. Disposed on the inner side of each of the traffic rails 12 is positioned a flangeway rail 16 having its upper or ball surface abutting the traffic rail web and its lower or flange surface abutting the intermediate crossway structure. Each of the filler members 14 has its side adjacent the upper surface thereof bevelled for receiving a channel iron member 17. These channel iron members 17 are positioned on the filler members 14 in an inverted position and their depending flanges are pro-

vided with bevelled faces for cooperating with the bevelled sides of the filler members 14, thereby forming a tight seal between the filler members and the edges of the depending channel iron flanges. These filler members and channel irons may be of any desired dimensions and of proper number used to complete the intermediate structure. Between the channel irons and on top of the spacing sticks 15 is disposed a pre-determined amount of asphalt or gravel and tar for forming a proper seal between the channel iron members. The top of the asphalt or other material is in a plane below the top surface of the channel iron members, whereby there is formed an irregular or anti-slip surface on the crossing. This feature may be readily observed from the drawings.

The approach to the track rails may also be provided with one or more filler members spaced apart by spacing sticks and provided with channel iron members in substantially the same manner, with the exception of the channel iron member adjacent the outer sides of the traffic rail, which should preferably contact with the outer side of the ball or upper portion of the traffic rail. In the forms shown, 14a indicates filler members included in the construction of the approach to the traffic rail, 15a the spacing stick therebetween, and 17a the channel irons which may be identical with those employed intermediate the traffic rail. 18 indicates the road pavement and 19 a layer of asphalt between the road pavement and the adjacent channel iron 17a. The bottom of the filler member 14a adjacent the outer sides of the traffic rails is bevelled as shown at 14b, for receiving and cooperating with the adjacent rail flange and tie plate.

In order to reinforce the crossings and to construct the same in such manner as to cause the entire structure to operate as a unit, the filler members 14 are rigidly fixed to the cross-ties by means of pins 21, after which the channel irons are placed in position and rigidly fixed to their respective filler members 14 by means of pins 22 which preferably are provided with a flat head and of sufficient length to extend through the filler member and well into the cross-tie.

In order to provide drainage along the traffic rails and to prevent the flangeway rail becoming displaced there is provided a novel supporting means comprising a plurality of U-shaped members 20, disposed in spaced relation along the inner side of the flange rails and about the heads of the rail spikes (see Figs. 4 and 5). This structure provides sufficient drainage and at the same time maintains the flangeway rail in its proper position.

In order to further rigidly connect the several elements of the crossing the spacing

sticks are preferably fixed to adjacent filler members by means of nails or spikes 23.

Occasionally it is desired to construct such a crossing at points in the traffic rail where a rail joint occurs. Fig. 3 illustrates such a crossing wherein 24 and 25 indicate the plates and bolts respectively forming the rail joint. At such a joint it will be necessary to cut away a section of the flangeway rail so that the unit will fit around the joint. This can be readily done by means of an acetylene torch and it will be noted also that it is only necessary to cut away the ball portion and web of the flangeway rail, leaving the flange part or bottom of the flangeway rail in contact with the adjacent filler and cooperating side of the channel iron member whereby the proper seal for excluding dirt and water from the inner structure of the crossing is maintained.

It is often advisable to provide an extension at the ends of such crossways. These extensions are not subjected to the strenuous traffic as the crossing proper. However, as a matter of safety, it is desirable to provide an extension at each end of the crossing. The herein illustrated structure, in Figure 1, illustrates such an extension, which is durable and comparatively cheap to provide. In the form shown, supporting members are shims 28 and are provided on the next co-operating ties 11 for supporting the extension members which may comprise a plurality of planks 29 or other suitable material. The supporting members or shims 28, are of such dimensions as to support the planks 29 in the same plane as the crossing proper, suitable means such as nails or spikes being provided for rigidly fixing the members 28 and 29 to the ties 11. When such extensions are provided the flangeway rails 16 are preferably extended in length to include the length of the extensions and further, the ends of the flangeway rails are bevelled as shown at 30, to provide a smooth entrance 110 for the flange wheels traveling thereover. The ends of the extension members 29 are also preferably beveled, as shown at 31.

A railway highway crossing constructed in accordance with the above has been found to be superior to any other type of crossing known to me. Further, such a crossing may be constructed from discarded materials, owned by all railroads and, therefore, at a considerable saving.

The means 20 for supporting the flangeway rail is a very important feature of the invention. This can be observed from the accompanying drawings, illustrating the manner in which the flangeway rail is disposed on the members 20 supporting both the ball and flange edges in such a manner as to positively prevent the sagging of the flange rail in either direction. Here again, in supporting the flangeway rail in this manner the seal

between the flangeway rail and the associated edge of the intermediate crossing is maintained, thereby preventing inferior substance and water from gaining entrance to the inner portion of the crossing thus adding greatly to the life of the latter.

Another important feature of the invention is the rigid manner in which the several elements of the entire structure are fixed together and form a crossing which may be considered a unit.

It is to be understood that the filler members, spacing sticks, channel irons, flangeway rails, flangeway rail supporting members and other elements of the crossing, may be of any desired dimensions. Other changes, modifications, substitutions, additions and omissions may be made in the structure without departing from the spirit and scope of the invention as defined in the appended claims.

What I claim is:

1. A railway highway crossing comprising a plurality of parallel disposed channel shaped members, arranged to present a flat upper surface, filler members for supporting said channel shaped members and fastening means disposed vertically through the channel shaped members and the cooperating filler members.

2. A railway highway crossing, comprising a plurality of parallel disposed channel shaped members, arranged to present a flat upper surface, filler members for supporting said channel members, spacing sticks intermediate the vertical sides of the filler members and fastening means disposed transversely through the cooperating spacing sticks and filler members.

3. A railway highway crossing, including a traffic rail, a flangeway rail disposed along its inner side and means for supporting said flangeway rail, the said means comprising a plurality of U-shaped members spaced apart and supported by the inner flange of said traffic rail.

4. In a railway highway crossing the combination with a railroad tie, a tie plate, a traffic rail, a spike for fixing said traffic rail and tie plate to said tie and means for supporting said flangeway rail, including a U-shaped member disposed about the head of the said spike.

5. In a railway highway crossing, including railway ties, traffic rails carried thereby and an intermediate structure between said traffic rails comprising a plurality of parallelly disposed filler members having their vertical sides bevelled adjacent their upper surface and a metal member disposed on the upper surface of each of said filler members, the said metal members having depending flanges for engaging the bevelled sides of said filler members.

6. A railway highway crossing comprising a permanently arranged unit, consisting of

channel shaped members, means for supporting said members in spaced relation and means for sealing the spaces between the said members.

7. A railway highway crossing comprising a combination with a pair of rails between which the crossing is arranged. Supporting members consisting of filler members of predetermined lengths, uniform spacing members arranged intermediate of the supporting members, inverted channel irons disposed on said supporting members and fastening means disposed vertically through the channel iron members and the supporting members.

8. A claim in accordance with claim 1, including an extension comprising a plurality of planks disposed in side by side relation and means carried by the usual railway ties for supporting the said planks in the same plane with the crossing proper.

9. A claim in accordance with claim 1, including an approach to the traffic rails, comprising channel iron members, disposed in parallel relation, the channel iron member adjacent the said traffic rail adapted to abut against the outer side of said traffic rail.

10. In a highway railway crossing an intermediate structure, comprising a plurality of parallel disposed filler members, spaced apart and rigidly fixed to the usual railway tie, inverted channel iron members disposed over the said filler members and a filling substance disposed between the adjacent sides of the said channel iron members and adapted to form a predetermined recess between the upper edges of cooperating channel iron members, whereby an antislip crossing surface is provided.

In testimony whereof I affix my signature. 105
JOHN W. CERNY.
